HOSE SUPPORT

Maxine Watkins Speller, White Plains, and Helen
Gray Hill, Port Washington, N. Y.

Application June 11, 1947, Serial No. 753,964

3 Claims. (Cl. 2—305)

1

This invention relates to a hose supporting device. This device is of the suspender type, adapted to extend over the user's shoulders, and while not limited to such use it is particularly adapted for use by women during pregnancy.

An object of the invention is to provide a hose supporting device which does not restrict the abdomen and is adapted to give a maximum of freedom for body movements.

Another object of the invention is to provide a suspender type of hose supporter which is substantially self-adjusting to accommodate movements of the user.

Another object of the invention is to provide a simple and practical device of the above mentioned kind.

Other objects of the invention will be in part obvious or in part pointed out hereinafter.

The invention accordingly consists in the features of construction, combinations of elements, arrangements of parts, and in the several steps and relation and order of each of said steps to one or more of the others thereof, all as will be pointed out in the following description, and the scope of the application of which will be indicated in the following claims.

The invention will best be understood if the following description is read in connection with the drawings, in which,

Figures 1 and 2 illustrate the application of an embodiment of the invention illustrated in Figure 3, Figure 1 being a front view and Figure 2 a rear view;

Figure 3 is a perspective view of a device embodying the invention; and

Figure 4 is a detail showing one form of loop structure by which the straps may be slidably interrelated at their points of crossing.

The term "strap" is used herein in a broad sense and is intended to include ribbon or strips of various other kinds of textile material and the like.

The supporter comprises the straps 10 and 12 each of which is long enough so that with its mid portion extending over one of the user's shoulders, its ends will reach to the top of the respective stockings worn by the user. The straps are crossed over the user's back, at 14, but are not crossed in front. Consequently the rear portion of each strap extends diagonally across the user's back and the front portion extends substantially straight down from the shoulder except as deflected by the adjustment and interconnecting means which will be described.

The end of the front half of one strap and the

end of the rear half of the other strap are crossed in the region of the thighs respectively, so that the end of the rear half provides attachment means for the stocking in front and the end of the front half provides stocking attachment means in the rear of the user's leg.

The said end of the front half of one strap and the said end of the rear half of the other strap are slidably related at their crossings in the region of the thigh, each strap being provided adjacent one end with a loop or eye through which the other end of the other strap may be inserted. Thus as shown herein strap 10 is provided with the loop or eye 10^a and strap 12 is provided with the loop or eye 12^a. The end of the rear half of strap 12 is threaded through the loop 10^a of strap 10 and the end of the rear half of strap 10 is threaded through the loop 12^a of strap 12.

20 The loops 10^a and 12^a are located so that when the supporter is in use, with straps 10 and 12 extending over the opposite shoulders of the user, they will be positioned substantially over the user's thighs respectively. Thus the clasp 10^b which is provided at the end of strap 10 which has been inserted through loop 12^a may be attached to the stocking top at the front of the user's right leg, and the clasp 10^c which is provided on the other end of strap 10 may be attached to the stocking top at the rear of the user's left leg.

25 Similarly the clasp 12^b at the end of strap 12 which has been threaded through loop 10^a may be attached to the stocking top at the front of the user's left leg, and the clasp 12^c on the other end of strap 12 may be attached to the stocking top at the rear of the user's right leg.

30 Thus the straps 10 and 12 are secured together in back of the user at 14, and the opposite ends of the straps are slidably related to one another 40 in the region of the user's thighs respectively.

The halves or portions of each strap 10 and 12 which extend down from the shoulder in front of the user's body are adjustably and slideably interrelated by the cooperating members 16 and 18. Member 16 is a short strap terminating at one end in the loop 20 through which one of the straps 10 or 12 is threaded and member 18 comprises a hook 22 carried by the loop 24 through which the other of said straps 10 or 12 may be threaded. Member 16 is provided with a plurality of eyelets 26 spaced at intervals providing a plural number of attachment means for hook 22. Thus members 16 and 18 cooperate to interconnect the front portions of members 50 10 and 12, and thus hold them in the desired

position in use and restrain them from any tendency to slip off the shoulders.

It will be understood that since the straps 10 and 12 are only slidably related with members 16 and 18 respectively relative movement between the front portions or halves of straps 10 and 12, and between the straps and said members 16 and 18, is afforded. The distance between the portions of straps 10 and 12 which extend down the front of the body may be adjusted as may be desired by selection of the particular eyelet 26 with which hook 22 is engaged. And because members 16 and 18 may be completely disconnected it is possible to put on the supporter by simply drawing or placing the straps over the respective shoulders, without the necessity of raising the arms.

Thus the device is adjustable by changing the point of engagement between members 16 and 18, and it is also self-adjusting on the body. The two straps 10 and 12 are interrelated and held in position but each is slideable relative to the other in front of the user's body and the opposite ends of the straps are slidably interrelated with the result that the device is self-adjusting in its position on the user in accordance with the movements of the user, and will permit the user to have a maximum of freedom of movement without pressure or constriction in the region of the waist or abdomen. Thus also a continuous, dependable stocking support is provided at all times, the pull on the clasps attached to each stocking being balanced and maintained substantially constant at all times irrespective of the movements of the user by the slipping and adjustment of one strap relative to the other.

It will thus be seen that there has been provided by this invention an article in which the various objects hereinabove set forth together with many thoroughly practical advantages are successfully achieved. As various possible embodiments might be made of the mechanical features of the above invention and as the art herein described might be varied in various parts, all without departing from the scope of the invention,

tion, it is to be understood that all matter hereinbefore set forth or shown in the accompanying drawing is to be interpreted as illustrative and not in a limiting sense.

5 What we claim is:

1. A hose supporting device comprising two straps adapted to extend over the user's shoulders respectively and to cross the user's back and extend down in front without crossing, the front end of each strap crossing and being slidably related to the rear end of the other strap, and an adjustable means slideable on said straps for controlling the distance between said straps in front of the user.

16 2. A hose supporting device comprising two straps adapted to extend over the user's shoulders respectively and across the user's back and extend down in front without crossing, stocking attachment means at the ends of said straps, and 20 means slideably interconnecting the uncrossed portions of the straps in front of the user to control the relative position of said uncrossed portions.

25 3. A hose supporting device comprising two straps adapted to extend over the user's shoulders respectively and across the user's back and extend down in front without crossing, stocking attachment means at the ends of said straps, and a connector slideably mounted on said straps for 30 controlling the distance between said straps in front of the user.
